UNITED STATES PATENT OFFICE.

ROBERT C. ELLIOTT, OF PRAIRIE CREEK, INDIANA, ASSIGNOR OF ONE-HALF
TO JAMES W. NEBERGALL, OF SAME PLACE.

RAILROAD-GATE.

SPECIFICATION forming part of Letters Patent No. 356,402, dated January 18, 1887.

Application filed September 16, 1885. Renewed December 16, 1886. Serial No. 221,752. (No model.)

To all whom it may concern:

Be it known that I, ROBERT C. ELLIOTT, a citizen of the United States, residing at Prairie Creek, in the county of Vigo and State of Indiana, have invented certain new and useful Improvements in Railroad-Gates; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a plan view. Fig. 2 is a vertical longitudinal section. Fig. 3 is a transverse section. Fig. 4 is a sectional view taken on the lines X X of Fig. 1.

This invention relates to gates on railroads, to prevent cows or other stock from passing down and across the track in the vicinity of crossings or at other points where they may have easy access to the track.

The gate is intended to take the place of the ordinary pits covered with bars, which are likely to break the legs of animals venturing thereon, and is so arranged that it will be thrown down automatically by the approaching train.

Referring to the accompanying drawings by letters, A designates a section of a railroad having the bearings *a a* secured to opposite points of its sides. In these bearings turns the shaft B, having at its center the double crank B', and at equal distances on each side of its center the single cranks *b b'*. The ends of the shaft B outside of its bearings are provided with the arms C C' at right angles to the shaft and extending in opposite directions, as shown. To the end of the arm C a cord or twine, *c*, is attached, which passes thence over the sheave D in a vertical bar, E, and has a weight, *d*, secured to its depending end. To the end of the arm C' a cord or wire, J, is attached, which passes thence over a sheave, D', in a vertical bar, E', and has a weight, *d'*, secured to its depending end. The weights *d* and *d'* are equal and balance each other, so that the bars *f*, which project upward from the shaft, and form the gate F stand vertical so in their normal position.

G is a lever-arm having one end journaled to the crank *b* of the shaft B, and extending thence to one side of the shaft B in proximity with the rail, to which it is held by the slot *g* in its end, and a bolt, *x*, passing through the rail and through said slot. The outer end of the lever-arm G is so formed that when the flange of the wheel of the locomotive presses upon it it will move far enough inward to rotate the crank *b* sufficiently to turn down the gate F.

G' is a lever-arm, similar to the lever-arm G, arranged on the other side of the shaft B, adjacent to the opposite rail, and connected similarly to the crank *b'* of shaft B. *g'* is a slot through the lever-arm G', and *x'* is the retaining-bolt, similar to and having the same function as the bolt *x* on the other side.

H and H' are longitudinal lever-arms situated centrally between the rails, running in opposite directions, each connecting at its inner end with the double crank B' on the shaft B, and arranged to slide in proper supports. The outer ends of the arms H H' are so formed that the arms can be moved by the approaching locomotive, and thereby turn the crank so as to depress the gate.

When the gate and weights are in their normal position, the latter cause the gate to stand erect and prevent the passage of cows or other stock; but upon the passage of the train the lever-arms G G' and H H' are so actuated as to depress the gate and allow the cars to pass thereover without striking the same.

It is obvious that when the cow-catcher of a locomotive strikes the lever-arms H H' it will turn the crank-shaft B, and consequently the gate, no matter what position the said crank-shaft may be in. It will also be perceived that by the employment of the levers G G' the gate will be prevented from rising until the last car has passed.

I am aware that it is not broadly new to arrange a railway-gate on a rock-shaft transversely of the track, and provide sliding levers in connection with the gate, which are adapted to be engaged by a traveling train to turn down the gate.

I am also aware that a rock-shaft carrying a gate has been provided with crank-arm shav-

ing weight-connections to keep the gate in its normal position.

Having thus described my invention, what I desire to secure by Letters Patent is—
5 The combination of a gate supported on a cranked rock-shaft, means for holding the gate in its normal position, the levers H H', having their outer ends arranged in slide-bearings and their inner ends connected to the crank-
10 shaft, and the similar levers, G G', connected

with the said shaft and arranged to be engaged by the wheels of a traveling car, substantially as specified.

In testimony whereof I affix my signature in presence of two witnesses.

ROBERT C. ELLIOTT.
